UNITED STATES PATENT OFFICE.

DAVID F. VAUGHAN, OF HADDONFIELD, NEW JERSEY.

GUARD-RAIL.

SPECIFICATION forming part of Letters Patent No. 752,428, dated February 16, 1904.

Application filed September 22, 1903. Serial No. 174,161. (No model.)

To all whom it may concern:

Be it known that I, DAVID F. VAUGHAN, a citizen of the United States, residing at Haddonfield, Camden county, New Jersey, have invented 5 certain new and useful Improvements in Guard-Rails, of which the following is a full, clear, and exact description, reference being had to the accompanying drawings, of which—

Figure 1 is a plan view, certain usual well-known parts being omitted. Fig. 2 is an enlarged section. Fig. 3 is an edge view of the guard-rail plate detached.

The object of this invention is to provide an attachment adapted to be applied to guard-rails whereby the part of the rail against which the flange of a car-wheel is liable to impinge is rendered more durable and whereby adjustment of the guard-rail with relation to the main or track rail, sometimes required 20 when the side of the head of the guard-rail becomes worn away, is obviated.

The precise nature of the invention will appear from the following description, reference being had to the drawings, in which 1 is 25 the main or track rail, and 2 the guard-rail.

In carrying out my invention I cut away a side of the guard-rail, as seen in Fig. 2, and provide a plate 3, made of very hard metal—as, for example, manganese-steel—of the form 30 shown—that is, substantially rectangular in cross-section, but with projections or enlargements 4 on one side at intervals (or it may be continuous along the plate) that are adapted to fit in the space formed by the under side of the head 5 of the rail, the top of the foot-flange 6, and the web 7. This plate 35 is applied to the guard-rail, as seen more clearly in Fig. 2—that is, the enlargements in said space and the part 3° of the plate against the cut-away head of the rail and the plate are 40 secured to the guard-rail by rivets 8, one of

which is shown in Fig. 2, passing through the web of the rail, the plate, and one of the enlargements 4. By the construction shown the plate is held firmly and securely in position and being of hard metal will wear a comparatively long time. The enlargement 4 may be dispensed with and the lower side of the plate extended, so that it will bear against the cut-away side of the flange 6.

Having thus described my invention, I claim as new and desire to secure by Letters Patent—

1. The combination with the guard-rail having the side of its head cut away of the hard-metal plate secured to the web of the rail with its upper portion bearing against said cut-away part of the rail, substantially as and for the purpose set forth.

2. The combination with the guard-rail, having the side of its head cut away, of the hard-metal plate having the side enlargement, the part of said plate above the latter being fitted against the cut-away side of the head of the rail, and said enlargement fitted in the space between the latter and the top of the foot-flange of the rail, together with means for securing said plate to the web of the rail, substantially as and for the purpose set forth.

3. The hard-metal plate substantially rectangular in cross-section and having the side enlargement adapted to fit against the web of a rail, substantially as and for the purpose set forth.

In testimony whereof I have hereunto affixed my signature this 15th day of September, A. D. 1903.

DAVID F. VAUGHAN.
